UNITED STATES PATENT OFFICE.

WILHELM SWOBODA, OF ALTON, AND BOLESLAW SWOBODA, OF EAST ST. LOUIS, ILLINOIS.

RAILWAY SAFETY-SIGNAL.

1,271,831.

Specification of Letters Patent.

Patented July 9, 1918.

Application filed July 7, 1916. Serial No. 107,921.

To all whom it may concern:

Be it known that we, WILHELM SWOBODA, a citizen of the United States, residing in Alton, in the county of Madison and State 5 of Illinois, and BOLESLAW SWOBODA, a subject of the Emperor of Austria, residing in East St. Louis, in the county of St. Clair and State of Illinois, have invented new and useful Improvements in Railway Safety-

10 Signals, of which the following is a specification.

This invention relates to railway safety apparatus such as employed for controlling trains passing along railway tracks. The 15 apparatus as disclosed in the following specification is intended to coöperate with a switch, in such a way that if a switch ahead of the train is in an unsafe position, the engineer on the locomotive will be given a 20 signal in time to prevent an accident. The apparatus for this purpose which is usually carried on locomotives frequently involves the use of two or more solenoids or electromagnets and also frequently includes 25 springs.

The general object of the present invention is to produce a very simple apparatus to be carried by the locomotive for the purpose stated and which will be reliable in 30 operation, at the same time avoiding the use of a great number of parts, and springs.

Further objects of the invention will appear hereinafter:

The invention consists in the general combination of parts and features to be described hereinafter all of which contribute to produce an efficient and reliable safety apparatus.

In the drawing which fully illustrates a 40 preferred embodiment of our invention, the figure is a diagrammatic view indicating the general arrangement and details of our apparatus as applied to an ordinary locomotive.

45 Referring more particularly to the parts, 2 represents the rails of the track, along which the locomotive 7 runs. At a suitable point on the track and at a considerable distance from the coöperating switch, we provide a track-device 19 to which is attached 50 a conductor or wire 24 which leads forward on the track and is connected with the switch point adjacent the near rail, as viewed in this figure. Near the location of the track 55 device the near rail is connected with the ground by a conductor 28. It should be un-

derstood that the conductors 24, 28 and the near rail form parts of an electric circuit including a battery or other source of E. M. F., said circuit being arranged so that when 60 the switch point is in a dangerous position the circuit will be closed through the conductor 24 when the locomotive arrives at the track device 19.

In order to complete the circuit through 65 the locomotive and cause an alarm to be given to the engineer we provide the locomotive with a contact device of any suitable construction, for example, comprising an arm 20 pivotally mounted on a bracket 23 70 secured near the forward end of the locomotive, said arm 20 being provided with a contact roller 21 at its lower end and being constrained toward an inclined position by a coiled spring 22. When the locomotive 75 arrives at the track device 19, the roller 21 rides upon the track device, thereby permitting the current to flow through a conductor 18 which is connected with the bracket 23. This conductor 18 is connected with a solenoid coil 12 which is preferably disposed with its axis substantially vertical, and within the coil there is provided a core 13, the upper end of said core being provided with a head 14 of insulating material which is of 85 sufficient diameter to engage the upper end of a coil and support the core within the coil, that is to say, it prevents the core from falling out of the coil. A similar insulating head 17 is provided at the lower end of the 90 core, the function of which is to engage the coil when the coil is energized and thereby limit the upward movement of the core.

In a position adjacent to the solenoid we provide a switch which preferably includes 95 a movable contact member 11 and a fixed contact member 15, both of which are mounted on an insulating block 10. When the coil 12 is not energized the movable contact 11 occupies a depressed position such as that 100 indicated by the dotted line 11^a. At all times this movable contact 11 lies above and in the path of the upper end or head 14 of the solenoid but is unattached to the head. The contacts 11 and 15 are connected in the 105 circuit 9 with an alarm device or electric bell 8, the said circuit being energized by a battery 16. The fixed contact 15 is constructed so that when the movable contact 11 rises it will resiliently engage the movable 110 contact 11 and hold it by frictional contact in its elevated position.

One end of the solenoid coil 12 is connected by a conductor 25 with the axle of the locomotive, through the medium of a contact or brush 26, the circuit being completed through the rim 27 of the wheel, by its contact with the near rail 2.

In the mode of operation of the apparatus, if the switch ahead on the track is in a dangerous position, the circuit will be closed through the locomotive when the locomotive arrives at the track device 19, through the medium of the arm 20 and the conductors 18 and 25. This energizes the coil 12 and operates to move the solenoid core 13 into its elevated position. As the core rises its head 14 engages and pushes up the movable contact 11 in its path of movement until the movable contact comes into frictional engagement with the resilient fixed contact member 15. As soon as the locomotive passes beyond the track device, the solenoid core descends by gravity to its normal position, leaving the switch 11-15 closed. As soon as the switch 11-15 closes, it closes a local circuit through the alarm or bell 8 and an alarm is given to the engineer. Furthermore this alarm will continue until the engineer seizes the movable contact 11 and depresses it to its normal position, breaking its contact with the switch member 15.

It is evident that the means described are very simple indeed, involving the use of a single solenoid coil and avoiding springs such as are usually associated with apparatus of this character.

We claim:—

1. In an apparatus of the class described, the combination of a solenoid coil, a core within said coil mounted in a substantially vertical position so as to be raised by said coil when energized by the current, a movable contact member for closing a circuit, unattached to said core and lying above and in the path of movement of said core so as to be actuated to close the circuit by the upward movement of said core, and a second contact member of resilient material to engage said movable contact member, and operating by engaging therewith to hold the same up and thereby maintain the circuit closed.

Copies of this patent may be obtained for five cents each, by addressing the "Commissioner of Patents, Washington, D. C."

2. In apparatus of the class described, the combination of a solenoid coil, a core within said coil mounted in a substantially vertical position so as to be raised by said coil when energized by the current, a movable contact member for closing a circuit, unattached to said core and lying above and in the path of movement of said core so as to be actuated to close the circuit by the upward movement of said core, and a second contact member of resilient material to engage said movable contact member, and operating by frictional contact with said movable contact member to hold the same up and thereby maintain the circuit closed.

3. In apparatus of the class described, the combination of a solenoid coil, a core within said coil mounted in a substantially vertical position so as to be raised by said coil when energized by the current, a movable contact member for closing a circuit, unattached to said core and lying in the path of movement of said core so as to be actuated to close the circuit by the upward movement of said core, said core being freely movable so as to be returned by gravity after being raised by said coil, and having a head at its upper end to engage said coil and support the core in its depressed position.

4. In apparatus of the class described, the combination of a solenoid coil, a core within said coil mounted in a substantially vertical position so as to be raised by said coil when energized by the current, a movable contact member for closing a circuit, unattached to said core and lying in the path of movement of said core so as to be actuated to close the circuit by the upward movement of said core, said core being freely movable so as to be returned by gravity after being raised by said coil, and having a head at its upper end to engage said coil and support the core in its depressed position, said core also having a lower head for engaging the lower end of said coil to limit the upward movement of said core.

In testimony whereof, we have hereunto set our hands.

WILHELM SWOBODA.
BOLESLAW SWOBODA.
